ABSTRACT: A horizontal deflection circuit in which the driver transistor is coupled to the output transistor via a transformer. In order to prevent oscillations in the output stage, a capacitor is shunted across the transformer secondary winding. The capacitor is chosen so that its impedance, at the line repetition frequency, is substantially smaller than the impedance of the secondary inductance, e.g., 3 to 5 times smaller.

CIRCUIT ARRANGEMENT FOR GENERATING A SAWTOOTH CURRENT

The present invention relates to a circuit arrangement for generating a sawtooth current through the horizontal deflection coil of a display tube. More particularly, to a deflection circuit provided with a final transistor whose output circuit includes the deflection coil and which is coupled to a driver transistor through a transformer. The secondary of the transformer is connected between base and emitter of the final transistor. A switching signal is applied to the base of the driver transistor which blocks and releases the final transistor through the transformer, the blocking period lasting longer than the flyback time of the sawtooth current. The final transistor is essentially an asymmetrical transistor so that at the beginning of the scan time the current through the deflection coil which is then reversed relative to the end of the scan time, can flow through the released base-collector diode of the final transistor. The supply voltage of the final transistor is many times higher, for example, at least 10 times higher than the peak-to-peak value of the switching signal applied through the transformer between base and emitter of the final transistor.

Such a circuit arrangement has been described in a copending application Ser. No. 579,539, filed Sept. 15, 1966, now U.S. Pat. No. 3,504,224.

This circuit arrangement operates perfectly under normal circumstances. It has, however, been found that the final transistor also becomes defective if the driver transistor becomes defective (can no longer conduct) or if a defect occurs in the control circuit of this driver transistor so that it can no longer be rendered conductive at the desired instants. Thus the drawback is that not only elements in the control circuit of the final transistor become defective, but that the final transistor itself becomes defective too. If the defect of the final transistor is found first during repair and if only this transistor is replaced, it may happen that the new final transistor may again become defective when power is applied to the circuit.

In order to obviate these drawbacks the circuit arrangement according to the invention is characterized in that the secondary of the transformer is shunted by a capacitor whose impedance at the repetition frequency of the sawtooth current is smaller than the impedance of the secondary inductance of the driver transformer.

As will be described hereinafter, the step according to the invention is based on the concept that due to energy being returned from the collector circuit to the base circuit through the base-collector diode of the final transistor, there is the possibility that the final transistor starts oscillating of its own accord if the driver transistor does not become conductive at the desired instants. In the event of self-oscillation, the control energy in the base circuit of the final transistor is in the end no longer able to maintain this final transistor in the saturated state so that the natural dissipation of this final transistor will be larger than under normal operating conditions. Furthermore, switching off is then effected much less abruptly, that is to say, the collector current turns to zero much more slowly than when the driver transistor becomes conductive. As a result the product of current and voltage during this gradual switching off will be much higher than when the collector current quickly returns to zero. Especially the latter effect causes very high dissipations.

This means that the normal on-off conditions are no longer satisfied during this self-oscillation, and since self-oscillation may continue through a few periods the overall dissipation of the final transistor becomes much higher than it can stand so that this final transistor is seriously damaged or even destroyed. Due to the step according to the invention, in which a capacitor is additionally connected on the secondary side, the possibility of self-oscillation is avoided and hence the final transistor is prevented from becoming defective if the control circuit becomes defective.

In order that the invention may be readily carried into effect, a few embodiments thereof will now be described in detail, by way of example, with reference to the accompanying diagrammatic drawings, in which:

FIG. 1 shows the known circuit arrangement according to the copending U.S. Pat. application Ser. No. 579,539;

FIG. 2 is a partial substitution diagram of the circuit arrangement of FIG. 1;

FIG. 3 shows the circuit arrangement according to the invention; and

FIGS. 4a-c show the collector current and collector voltage of the final transistor both in normal use and when the driver transistor does not become conductive unless the step according to the invention is taken.

Except for the series inductance L_B , the operation of the circuit arrangement of FIG. 1 has been described in the aforesaid copending U.S. Pat. application so that it is sufficient to mention herein the switching elements used.

15 The circuit arrangement of FIG. 1 consists of driver transformer 1 having a primary 2 which is connected in the collector circuit of a driver transistor T_1 to whose base circuit the control signal 3 is applied. The secondary 4 of the transformer 1 is connected between base B and emitter E of the final transistor T_2 . The collector circuit of T_2 includes the parallel arrangement of a deflection coil L_y and a capacitor C_y connected parallel thereto and which circuit is supplied from a voltage source V_H .

25 The operation of the series inductance L_B has been described in my copending U.S. Pat. application Ser. No. 737,009, filed June 14, 1968 and this inductance L_B is provided to ensure that the collector current of the final transistor T_2 returns as quickly as possible from a given final value to zero at the end of the scan time of the sawtooth current flowing through the coil L_y .

30 FIG. 2 shows that partial substitution diagram of the circuit arrangement of FIG. 1. The last-mentioned FIG. shows that a current I_{c1} flows which accumulates electromagnetic energy in the coupling inductance L_x when the driver transistor T_1 functions at instants when it is conducting (switch T_1 shown in FIG. 2 closed). The current I_{c1} flows in the primary circuit of the transformer 1 and will therefore be referred to hereinafter as "primarily supplied energy."

35 FIG. 2 also shows that a current $I_{c2}=I_{B2}$ flows in the secondary circuit which likewise accumulates energy in the coupling inductance L_x . The last-mentioned energy will be referred to as "secondarily supplied energy." In practice, the "primary energy" strongly prevails to normal operation relative to the "secondary energy." This is due to the fact that switch T_1 , in the closed condition can substantially be regarded as a short circuit since the driver transistor T_1 is then substantially in saturation. Viewed from the secondary, substantially the short circuit is seen instead of the inductance L_x . However, the inductance L_B , the internal resistance of the base (B)-collector (C) diode D_{c2} and the parallel arrangement of capacitor C_y and coil L_y are seen, as viewed from the primary. Therefore, when switch T_1 is closed it is only necessary to take the primary energy into account (in all these cases the internal resistances of the voltage sources V_s and V_H have been assumed to be substantially nil while also the leakage inductances of the transformer 1 have been ignored). Since conduction of transistor T_1 is controlled by the control signal 3 applied to its base, this means that the instants at which and the extent to which energy is supplied to the inductance L_x are completely determined.

40 If, on the other hand, transistor T_1 does not become conductive because this transistor itself becomes defective or because there is something wrong in its control circuit, then the primarily supplied energy drops out and hence the control of the control circuit of the final transistor T_2 is lost.

45 In the latter case the secondary energy starts to play an uncontrolled part. This secondary energy is larger than the situation where the primary energy is actually supplied. In fact, as viewed from the secondary, a short circuit is not seen any longer, but the inductance L_x is seen. The energy returned from the coil L_y therefore accumulates in the inductances L_x and L_B .

50 If collector current I_{c2} and voltage V_{ce2} of transistor T_2 are considered, the following appears. FIG. 4a shows the collector

current I_{c2} and FIG. 4b shows the collector voltage V_{ce2} of the transistor T_2 if driver transistor T_1 functions satisfactorily. In FIG. 4c line 5 shows the collector current I_{c2} , line 6 shows the collector voltage V_{ce2} and line 7 shows the current I_{ly} flowing through the deflection coils L_y if the transistor T_1 does not become conductive. Here the transistor T_1 is assumed to become defective after a satisfactory flyback period $0-t_1$ and subsequent control period t_1-t_2 as is shown in the left-hand part of FIG. 4c. If the transistor T_1 would become defective during the period $0-t_2$, the primary energy drops out somewhat earlier and the phenomenon is perhaps less pronounced but is not different in principle. Since the scan period is longer than the period $0-t_2$ the risk of defect during the scan period is greatest.

As the instant t_4 at which T_1 starts to conduct, under normal circumstances, the energy in the inductances L_x and L_B is not yet zero and therefore base current and thus collector current continue to flow in the final transistor T_2 . This will result in a decrease of this residual energy after the instant t_4 . However, since new energy is not supplied for the time being to inductances L_x and L_B , the transistor T_2 cannot be bottomed for too long a period after the instant t_4 and it has been assumed that transistor T_2 comes out of a bottomed condition at the instant t_5 . The collector current I_{c2} will then remain at a slightly constant value for a short period t_5-t_6 and subsequently, during the period t_6-t_7 , will decrease to zero. At the instant t_7 the energy in L_x and L_B is zero and hence the base current I_{B2} and consequently the collector current I_{c2} are likewise zero.

Energy is again accumulated in the deflection coil L_y during the period t_5-t_6 and this energy will tend to start a free oscillation across capacitor C_y when the collector current I_{c2} is switched off during the period t_6-t_7 . This oscillation current is indicated by line 7 in FIG. 4c. This actually means that energy is applied back to the inductances L_x and L_B at the end of the oscillation period through the then released base-collector diode D_{c2} so that the energy accumulated in these inductances may again produce base-current I_{B2} in the final transistor T_2 . This means that the entire phenomenon as indicated in FIG. 4c is repeated, as often as is possible, depending upon the circuit losses. If these losses are small, however, this so-called self-oscillation may continue for a rather long time, the source V_H actually functioning as a supplier of energy. Of course this self-oscillation might be eliminated by adding some attenuation in the secondary circuit. However, this attenuation would then be active under normal operating conditions too and would considerably reduce the efficiency of the circuit arrangement. Thus this latter solution is not considered because it is impractical.

If the collector voltage V_{ce2} is considered, which occurs when driver transistor T_1 does not become conductive, the dissipation of final transistor T_2 appears to have increased considerably. This is apparent from FIG. 4c in which line 6 represents the collector voltage V_{ce2} . As long as the transistor T_2 is still bottomed, the collector voltage V_{ce2} will deviate little from zero so that the product of current and voltage, which determine the natural dissipation of the transistor T_2 , is still rather small. If, however, the transistor T_2 is no longer bottomed after the instant t_5 , the collector voltage and hence the product of current and voltage rapidly increase. However, particularly due to the slow switching off during the period t_6-t_7 , the natural dissipation of transistor T_2 increases considerably. This is particularly to be ascribed to the fact that the voltage V_{ce2} increased considerably during this period and the current still has a substantial value over a large part of the latter period. Consequently, the development of heat in the final transistor T_2 will have disastrous results, especially if the phenomenon of self-oscillation continues over a few periods.

In order to prevent the self-oscillation a capacitor 8 of comparatively high value is connected parallel to the secondary 4 of the transformer 1 , as is shown in FIG. 3. The capacitor 8 is also shown by a broken line in the substitution diagram of FIG. 2. The value of the capacitor 8 is chosen so that its impedance at the repetition frequency of the sawtooth current is small

relative to the impedance of the secondary inductance L_2 of the transformer 1 . A suitably chosen value provides an impedance for the capacitor 8 at the repetition frequency of the sawtooth current which is approximately 3 to 5 times smaller than the impedance of this secondary inductance L_2 .

The fact that self-oscillation is then indeed avoided can be explained as follows. If, in fact, transistor T_1 is defective, the secondary circuit does not see the coupling inductance L_x , which is then actually formed by the secondary inductance L_2 , but sees the parallel arrangement of said inductance L_2 and the capacitor 8 . The portion of the current I_{c2} which flows to the coupling inductance L_x is then decreased to such an extent that the energy resupplied in this coupling inductance L_x is too small to allow self-oscillation to occur. In other words, due

15 to the additional connection of the capacitor 8 the apparent inductance which is present in the secondary circuit is smaller than the originally present inductance L_x . Since the coil L_y , which is the supplier of energy when the base-collector diode D_{c2} conducts, can be considered a current source, the current flowing through the parallel arrangement of L_x and C_8 remains the same, but the energy accumulated in the apparent inductance L_{sch} is smaller than that which occurs in coil L_x without the added connection of capacitor 8 . ($\frac{1}{2}L_x I^2 c_2 > \frac{1}{2}L_{sch} I^2 c_8$, because $L_x \gg L_{sch}$). The higher the value of the capacitor 8 the smaller the energy accumulated in the apparent inductance L_{sch} and the smaller the risk of self-oscillation of the circuit arrangement. However, one cannot go too far in increasing the value of capacitor 8 since then the primary energy also will become too small at a given instant to render a satisfactory normal action of the circuit arrangement possible.

20 Of course, it is possible to go quite far in increasing the value of capacitor 8 because the supply of the primary energy is a task of the driver transistor T_1 . If, therefore, the value of capacitor 8 is increased, a higher collector current will flow during the periods that driver transistor T_1 conducts because there must always be sufficient energy in the coupling inductance L_x to allow a sufficiently high base current I_{B2} to flow in the final transistor T_2 after reblocking the driver transistor T_1 . However, by choosing the transformation ratio n of the transformer 1 to be slightly larger it can still be achieved that even with a capacity 8 of comparatively high value, too high a collector current need not flow in the driver transistor T_1 . In fact, primary 2 has n times as many turns as

25 the secondary 4 so that the secondary inductance L_2 appears in the primary circuit while being stepped up approximately n^2 times. The same applies to the capacitor 8 which, however, will be reflected in the primary circuit while being reduced n^2 times. The result is that this difference on the primary side is increased n^2 times if it is ensured that the impedance of the capacitor 8 is smaller than the impedance of the secondary inductance L_2 . Thus if n is chosen to be comparatively large, the required collector current of the driver transistor T_1 can also be considerably smaller than when a transformation ratio $1:1$ is employed. If it is assumed that the peak-to-peak value of the switching signal between base and emitter of the transistor T_2 is approximately 7 volts and that the supply voltage V_s of the driver transistor T_1 is approximately 130 volts, then a value of $n=20$ is obtained, so that n^2 becomes 400. Such a transformation ratio will therefore still ensure that the collector current of the driver transistor T_1 need not become much higher even when a capacitor 8 of comparatively high value is provided.

30 It has been assumed in the foregoing that the transformer 1 has substantially no leakage inductance. Even if leakage inductance is present, the provision of capacitor 8 would still add to the effect. In fact, in that case the secondary current $I_{c2}=I_{B2}$ first meets the capacitor 8 and therefore tends to start flowing through this capacitor and to a lesser extent through the series arrangement of leakage inductances and coupling inductance L_x . On the primary side, however, the primary current I_{c1} first meets the coupling inductance L_x and only thereafter does it meet the capacitor 8 through the secondary dispersion inductances. Therefore, the primary current in the coupling inductance L_x is preferred to the secondary current

which slightly simplifies the supply of primary energy under normal operating conditions relative to the case where no dispersion inductances are provided, and slightly hampers the supply of secondary energy if the driver transistor T_1 does not become conductive.

It is to be noted that the capacitor 8 must absolutely not shunt the series inductance L_B , too. In fact, as already stated L_B serves to ensure that under normal operating conditions the collector current I_{c2} of the final transistor T_2 returns as quickly as possible to zero at the end of the scan time. This function of L_B must not be tampered with.

A few practical values of a circuit arrangement according to FIG. 3 are the following.

Transformation ratio $n=20$

Secondary inductance $L_s=500 \mu\text{H}$.

Series inductance $L_B=22 \mu\text{H}$.

Capacitor $8=470 \text{ k.p.F.}$

Driver transistor $T_1=\text{Philips type B.C. 115}$.

Final transistor $T_2=\text{Philips type B.U. 105}$.

Capacitor $C_s=2.4 \text{ k.p.F.}$

Inductance $L_y=2.1 \text{ H.}$

Supply voltage $V_s=V_H=130 \text{ volts.}$

I claim:

1. A deflection circuit for producing a sawtooth current having a given flyback period on a deflection coil comprising, a unidirectional output transistor having an output circuit to which the deflection coil is connected, a driver transistor, a transformer coupling the output of the driver transistor to the base and emitter of the output transistor, a source of pulsatory switching signal coupled to the base of the driver transistor by means of which the driver transistor, via said transformer, supplies a switching signal that causes the output transformer to periodically turn on and off, the duration of the off period being longer than said given flyback period whereby a reverse current flows in said deflection coil and the base-collector junction of said output transistor at the start of the forward stroke of said sawtooth current, means for coupling a supply voltage to the output transistor that is at least 10 times the peak-to-peak voltage of the switching signal applied between the base and emitter of the output transistor, and a capacitor connected in shunt with the secondary winding of the trans-

former, said capacitor being chosen so that, at the repetition frequency of the sawtooth current, it has an impedance that is smaller than the impedance of the secondary inductance of said transformer.

- 5 2. A deflection circuit as claimed in claim 1 wherein the impedance of the capacitor at the repetition frequency of the sawtooth current is approximately 3 to 5 times smaller than the impedance of the secondary inductance of the transformer.
- 10 3. A deflection circuit as claimed in claim 1 wherein the primary winding of the transformer has approximately 20 times as many turns as the secondary winding.
- 15 4. A deflection circuit for producing a sawtooth current in a deflection coil comprising, a transistor having an output circuit connected to said deflection coil and an input circuit including inductive coupling means coupled to the transistor base and emitter electrodes, a source of pulsatory switching voltage coupled to said input circuit to periodically drive said transistor into a conductive state and a cutoff state, the duration of the cutoff period being longer than the sawtooth flyback period, a source of direct supply voltage coupled to said transistor and of a magnitude that is many times higher than the peak-to-peak amplitude of the switching voltage, and a capacitor connected in shunt with said inductive coupling means.
- 20 5. A deflection circuit as claimed in claim 4 wherein said inductive coupling means comprises a transformer having its primary winding coupled to the output of a driver transistor and a secondary winding coupled to the base and emitter of the output transistor and across which said capacitor is connected, the impedance of said capacitor, at the repetition frequency of the sawtooth current, being smaller than the impedance of said secondary winding.
- 25 6. A deflection circuit as claimed in claim 5 further comprising an inductor connected between said secondary winding and base electrode of the output transistor, and wherein said supply voltage is at least 10 times the value of the switching voltage.
- 30 7. A deflection circuit as claimed in claim 5 wherein the primary winding of the transformer has a greater number of turns than the secondary winding.
